(57) **CLAIM**

The ornamental design for a tire as shown and described.

DESCRIPTION

FIG. 1 is a front perspective view of a tire showing the claimed design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged view of the portion between lines 8-8 and 8'-8' in FIG. 2; and,

FIG. 9 is an enlarged cross-sectional view taken along line 9-9 in FIG. 8.

In the drawings, the broken lines show portions of the tire that form no part of the claimed design. The broken lines immediately adjacent to the sidewall features shown in solid lines represent the boundary of the claim and form no part thereof.
